ABSTRACT

An electronic musical instrument includes two different music part playing sections such as an organ section and a rhythm section. The tone signal from the organ section is applied to an amplifier followed by a loudspeaker through a variable resistor for expression control, while the tone signal from the rhythm section is applied to the amplifier through a resistor having a resistance higher than the minimum resistance of the variable resistor and lower than the maximum resistance of the same. The input sides of both resistors are shunted by another resistor having a resistance comparable with the output impedance of the playing sections. When the variable resistor is operated, the rhythm section signal is subjected to volume control of a narrower range than the organ section signal.

**ELECTRONIC MUSICAL INSTRUMENT WITH
EXPRESSION CONTROL DEVICE FOR
SIMULTANEOUSLY CONTROLLING DIFFERENT TONE
SIGNALS BY DIFFERENT AMOUNTS**

BACKGROUND OF THE INVENTION

This invention relates to an electronic musical instrument and more particularly to an expression control network therefor for controlling in different ranges the tone signals from different music part playing sections, such as an organ section and a rhythm section.

With an electronic musical instrument, such as an electronic organ, there is customarily incorporated a rhythm sound playing section, some manual and some automatic, as well as a normal musical scale tone playing section (organ section).

A normal electronic organ is provided with an expression pedal to control the volume of audible sounds to be produced.

Accordingly, it is desired to control by the expression pedal the volume of percussion (e.g. cymbals, maracas, claves, and drums) sounds produced by the rhythm section incorporated into the organ as well as that of organ sounds. It is, however, not desired to control the percussion sounds by the common organ expression pedal with the same characteristics as the organ sounds produced by the organ. The reason will be easily appreciated by taking into consideration a practical performance with a natural melody instrument and a natural rhythm (percussion) instrument.

The volume variation range of a normal rhythm instrument such as a drum is relatively narrow as compared with that of a melody instrument. The rhythm instrument maintains, therefore, a certain sound intensity even when the sound of the melody instrument is low. In view of the foregoing, accordingly, it has been contemplated to control the rhythm sounds produced by the rhythm section and the melody sounds produced by the organ section in an independent manner with separate control means. However, such separate control means give rise to complexities in construction and operation.

It is, accordingly, an object of this invention to provide an electronic musical instrument such as an electronic organ having a novel expression control network which permits volume controls of different ranges for signals from different music part playing sections, respectively.

Another object of this invention is to provide an electronic musical instrument having an organ section and a rhythm section, in which instrument the rhythm section sounds are controlled in volume within a narrower range than the organ sounds by means of the common expression pedal.

SUMMARY OF THE INVENTION

According to this invention there is provided an electronic musical instrument comprising two different music part playing sections (e.g. an organ section and a rhythm section), a novel expression control network for receiving tone signals from the both playing sections and controlling the volumes thereof, an amplifier for amplifying signals from the expression network and a loudspeaker for converting signals from the amplifier into audible sounds; wherein the expression network includes a first input terminal for receiving a tone signal derived from one of the playing sections, a second input terminal for receiving a tone signal derived from the other of the playing sections, an output terminal for delivering a tone signal to the amplifier, a first resistor connected between the first input terminal and the output terminal and having a resistance variable for expression control by a manual operation, a second resistor connected between the second input terminal and the output terminal and having a resistance fairly higher than the minimum resistance of the first resistor and fairly lower than the maximum resistance of the same, and a third resistor connected between the first and second input terminals and having a resistance comparable with the output impedance of the playing sections.

BRIEF DESCRIPTION OF THE DRAWINGS

FIG. 1 shows a block diagram embodying an electronic musical instrument according to this invention;

FIGS. 2A and 2B are two equivalent circuits in two electrical conditions of the expression control network shown in FIG. 1;

FIG. 3 shows a control characteristics diagram obtained with the expression control network of the present invention; and

FIG. 4 illustrates an expression pedal arrangement according to the present invention.

DESCRIPTION OF THE PREFERRED EMBODIMENT

Referring to FIG. 1, the invention is explained with reference to an embodiment of an electronic musical instrument which includes an organ section 1 and a rhythm section as two different music part playing sections. In the organ section 1, as is well known, outputs from tone generators 2 are coupled to a keyboard section 3, and outputs from the keyboard section 3 are coupled to tone coloring filters 4. With a conventionally designed electronic organ, in practice, the keyboard section 3 generally includes an upper keyboard for melody performance, a lower keyboard for chord performance, and a pedal keyboard for bass performance. The tone signals are selectively derived from the tone generators 2 upon operation of the respective keyboards, and the derived tone signals are fed into the respective tone coloring filters to obtain musical tone signals having proper timbres.

The reference numeral 5 denotes a rhythm section, which may be of a manual play type or may be of an automatic play type. One example of the rhythm section 5, as shown, may include generators 6 for producing percussion sounds such as drums, tom-toms, wood blocks and cymbals and outputs of the generators 6 are coupled to keyers 7 and in turn to tone coloring filters 8. The keyers 7 may include, for example, keyboard operated switches or switching circuits for the manual play type, or pulse triggered switching circuits associated with a rhythm pattern pulse generator and rhythm selector switches 40 for the automatic play type.

Output signals of the organ section 1 and the rhythm section 5 are hereinafter referred to as "organ signal" and "rhythm signal" respectively.

In accordance with the present invention, there is provided a novel expression control network 9 to control the levels of the organ and rhythm signals. The network includes first, second and third resistors R_1 , R_2 and R_3 as shown. The output of the organ section 1 is coupled to a first input terminal A via a resistor R_4 , and in turn to an output terminal O through the first resistor R_1 such as CdS device whose resistance varies in accordance with amount of light irradiated thereto. The output of the rhythm section 5 is coupled to a second input terminal B via a resistor R_5 and in turn coupled to the output terminal O through the resistor R_2 whose resistance is fairly large as compared with the minimum value of the variable resistor R_1 and is fairly small as compared with the maximum value thereof. The output terminal O is connected to an amplifier 10 and in turn to a loudspeaker.

A typical value for the resistor R_2 is around $200\text{ k}\Omega$ in the case that the resistor R_1 varies over a typical range of $10\text{ k}\Omega$ to $1\text{ m}\Omega$. The resistors R_4 and R_5 may be the inherent output impedances of the respective sections 1 and 5, typical values for the resistance R_4 and R_5 being together around $10\text{ k}\Omega$. Otherwise, separate additional resistors should be provided if each section includes a last stage, such as an emitter follower, having too low an output impedance.

The input terminals A and B are interconnected by the resistor R_3 whose value is comparable with the output impedance R_4 and R_5 and is desirable to be fairly small as compared with the resistor R_2 , a typical value therefor being around $10\text{ k}\Omega$.

The amplifier 10 has an input impedance, or a load for the network 9. The amplifier input impedance is represented by a resistor R_6 in the drawing, a typical value therefor being around $100\text{ k}\Omega$.

The variable resistor R_1 above-mentioned is preferably a light sensitive resistor irradiated by a light source 12 connected across a suitable power source (not shown), and the amount of light applied to the resistor R_1 is controlled by a shutter 13 disposed between the resistor R_1 and the light source 12 and arranged to move with an expression pedal. As shown in FIG. 4, the shutter 13 is perforated with an opening 14 in the form of an arcuate triangle. The width of the opening 14 increases gradually from one end to another end. When the expression pedal is not operated by the foot, the light beam to be applied to the resistor R_1 is restricted or blocked by the minimum width of the opening 14 of the shutter 13 and in consequence the value of the resistor R_1 becomes maximum ($1 \text{ M}\Omega$). When the expression pedal is completely depressed by the foot the maximum light amount is applied to the resistor R_1 by virtue of the maximum width of the opening 14 , and in consequence the value of the resistor R_1 becomes minimum ($10 \text{ k}\Omega$).

As described above, the resistor R_1 has the maximum value $1 \text{ M}\Omega$ when the expression pedal is not operated. The value is sufficiently large as compared with those of the resistors R_2 and R_3 connected in series across the resistor R_1 . In this case, accordingly, the equivalent circuit of the expression control network 9 will be as shown in FIG. 2A. On the other hand, the resistor R_1 has the minimum value $10 \text{ k}\Omega$ when the expression pedal is completely depressed. In this case, contrary to the foregoing, the resistor R_2 can be neglected with respect to the resistor R_1 . Accordingly, the equivalent circuit of the expression control network 9 will be as shown in FIG. 2B.

In FIGS. 2A and 2B, the organ section 1 and the rhythm section 5 are respectively shown by sources e_o and e_R each having zero internal impedance.

As shown in FIG. 2A, organ and rhythm signals e_o and e_R are together fed into the amplifier 10 through the resistor R_2 when the resistor R_1 has the maximum value ($1 \text{ M}\Omega$). In this case, however, the signal e_o will be divided by means of the resistor R_3 ($10 \text{ k}\Omega$) and the resistor R_5 ($10 \text{ k}\Omega$), and the signal level for the e_o signal at point B will be one half the signal level at point A. Namely, assuming that the signal e_o has the same level as the signal e_R , the level of the signal e_o is smaller than that of the signal e_R by about 6 dB at point B.

As shown in FIG. 2B, the signals e_o and e_R are together fed into the amplifier 10 through the resistor R_1 when it has the minimum value ($10 \text{ k}\Omega$). In this case, contrary to the foregoing, the signal e_R will be divided into half at point A by means of the resistor R_3 ($10 \text{ k}\Omega$) and the resistor R_4 ($10 \text{ k}\Omega$), and the signal level for the e_R signal at point A will be one half the signal level at point B. It will be appreciated, under such conditions as above-mentioned, that the level of signal e_R is smaller than that of signal e_o by about 6 dB at point A.

FIG. 3 shows a control characteristic diagram of the levels of signals e_R and e_o as a function of the value of resistor R_1 which varies continuously from the maximum value to the minimum value in accordance with operation of the expression pedal. In the drawing, the broken line C shows the control characteristic with respect to the signal e_o and the full line D with respect to the signal e_R .

As can be seen from FIG. 3 and the foregoing description, the volume of rhythm sounds based on the signal e_R is larger than that of organ sounds based on signal e_o by about 6 dB when the expression pedal is not operated, that is to say, when the operation angle of the expression pedal is minimum, and contrary to the foregoing, the volume of organ sounds based on the signal e_o is larger than that of rhythm sounds by about 6 dB when the expression pedal is completely depressed, that is to say, when the operation angle of the expression pedal is maximum.

It will be appreciated that, in accordance with the present

invention, the rhythm signal can be controlled in its level more narrowly than the organ signal irrespective of operation of the common expression pedal.

Although the description has been made with reference to an embodiment having an organ section and a rhythm section, it will be apparent to those skilled in the art that the invention can be utilized in other ways. For example, the one of the different music part playing sections may include an upper manual and a lower manual, while the other includes a pedal keyboard. Still further variations can also be applicable to the inventive concept.

What is claimed is:

1. An electronic musical instrument comprising at least two different music part playing sections, an expression control means for varying the volume of the tone signals from said different playing sections simultaneously and by different amounts, an amplifier and a loudspeaker; said expression control means including
  - an expression controller;
  - a first input terminal for receiving a tone signal derived from one of said playing sections;
  - a second input terminal for receiving a tone signal derived from the other of said playing sections;
  - an output terminal for delivering a tone signal to said amplifier;
  - a first variable resistance means connected between said first input terminal and said output terminal and having a resistance which is variable responsive to operation of said expression controller, said tone signal from said one playing section passing through said first variable resistance means to said output terminal;
  - a second resistor connected between said second input terminal and said output terminal and having a resistance higher than the minimum resistance of said first variable resistance means and lower than the maximum resistance of said first variable resistance means, said tone signal from said other playing section passing through said second resistor to said output terminal; and
  - a third resistor connected between said first and second input terminals and having a resistance approximately the same as the output impedance of said playing sections.
2. The electronic musical instrument according to claim 1, wherein said at least two different music part playing sections comprise an organ section and a rhythm section.
3. The electronic musical instrument according to claim 1, wherein said first variable resistance means includes a light sensitive variable resistor.
4. The electronic musical instrument according to claim 1 wherein said first resistance means includes a variable resistor whose value varies in accordance with amount of light irradiated thereto, said expression controller includes a manually operated expression pedal, and said expression control means further includes a light source for irradiating light to said light variable resistor, and a shutter means disposed between said light source and said light variable resistor and arranged to move with said expression pedal, said shutter means having an opening for controlling amount of light from said light source to said light variable resistor in accordance with operation of said expression pedal.
5. The electronic musical instrument according to claim 4 wherein said shutter means comprises a plate having a tapered opening therein disposed between said light source and said light variable resistor, the portion of said tapered opening through which said light source communicates with said light variable resistor varying in accordance with operation of said expression pedal, thereby varying the resistance of said light variable resistor.
